UNITED STATES PATENT OFFICE.

JOHN R. REPROGLE, OF DETROIT, MICHIGAN, ASSIGNOR TO ELECTRIC REFRIGERATION CORPORATION, OF DETROIT, MICHIGAN, A CORPORATION OF MICHIGAN.

MECHANICALLY-REFRIGERATED CABINET.

Application filed January 28, 1927. Serial No. 164,169.

This invention relates to mechanically refrigerated cabinets of the type in which different ranges of temperature are maintained in a plurality of food storage compartments.

- 5 An object of this invention is to provide a mechanically refrigerated cabinet for the storage of food and the like in which the circulation of a heat absorbing fluid contacting with a cooling unit and food containers
- 10 in a plurality of compartments is controlled to respectively regulate the temperature maintained in the different compartments.

Another object of the invention is to provide a mechanically refrigerated cabinet of 15 the multiple communicating compartment type having a heat absorbing fluid circulating through the communicating compartments and in contact with a cooling unit, with a manually operated valve mechanism 20 for controlling the flow of the heat absorbing fluid from one compartment to the other to regulate the temperature maintained in one of said compartments.

These and other objects will be more apparent as the description progresses, in which like characters designate like parts in the drawings illustrating a preferred embodiment of the invention.

In the drawings:

- 25 Fig. 1 is a view partly in section showing the brine tank construction and the arrangement of the evaporator with respect to the food storage receptacles.

Fig. 2 is a vertical transverse section taken 30 on the line 2-2 of Fig. 1.

Figs. 3, 4 and 5 are detail sectional views of the valve structure taken substantially on the lines 3-3, 4-4 and 5-5 of Fig. 2.

The cabinet structure hereinafter described in detail, and with which my invention is associated, is especially adapted for the storage of ice cream, bottled liquids and the like. The cabinet comprises the bottom wall 10 and the side walls 11, preferably 40 constructed of insulating material, and which are covered externally with metal covers and lined on the inside with a metal lining 12, preferably a non-corrosive material. The top wall 13 is secured in any suitable manner to the side walls and is covered 45 with a metal cover 14, preferably of "Monel" metal which is non-corrosive and very suitable for cabinet structures of this character. Supported within the cabinet is a closed tank 50 containing a brine or other suitable heat

absorbing fluid, and provided with a partition wall 16 which divides the tank into two compartments A and B. A cooling element or evaporator C is arranged to extend within the compartment A and the fluid therein, 50 and is connected in circuit with a conventional type of mechanical refrigerating apparatus (not shown).

This cabinet is constructed to permit the storage of foods, which are best preserved 55 by being maintained at different temperatures, such as ice cream, liquid bottled goods and the like. One or more open top food storage sleeves or receptacles 18 are arranged to extend within the tank and register with openings in the top wall, these openings being closed by the covers 19 so that access may be easily had to the interior of the food storage receptacles when the covers are removed. The heat absorbing 60 fluid, preferably cold brine, is arranged to be circulated through the compartments A and B and arranged to contact with the single cooling unit so as to permit both compartments to be chilled. Preferably the 65 cooling unit is positioned within one of these compartments, the drawings showing the evaporator C solidly supported within the compartment A. Obviously, additional partitions can be used when additional compartments are required.

In order to regulate the temperature of the compartment B the circulation of the brine from one compartment to the other is controlled in such a way as to regulate the 70 amount of heat units transmitted from compartment B to compartment A. The more heat units that are permitted to flow from compartment B to compartment A, the lower will be the temperature within the compartment B. The partition 16 is provided with a permanent opening 20 therethrough along the bottom edge for connecting compartment A with compartment B, and near the top edge of the partition wall 16 the sleeve or tube 21, preferably circular, in cross section, is soldered or otherwise secured in place providing a passageway which connects compartments A and B near the top. These openings permit the brine to circulate 75 from one compartment to another. The partition wall 16 is preferably constructed of metal panels 16^a and 16^b spaced apart to provide a dead air space therebetween, which serves to restrict the conduction of heat 80

through the wall. Fillers 16^c may be inserted between the spaced metal panels to prevent the pressure of the brine from buckling the metal panels 16^a and 16^b, thus serving to maintain a uniform spacing of the panels of the wall structure. These spaced members are preferably constructed of insulating material such as wood. In addition, the material of which the wall panels are constructed may be one of low heat conductivity to further restrict the conduction of heat through the wall. Pivoted within the tubular sleeve 21 is a butterfly valve 22, this valve being secured to the valve stem 23 extending vertically upward and terminating in the handle 24 exteriorly of the cabinet, which permits the butterfly valve to be manually adjusted from without the cabinet for controlling the circulation of the brine.

The operation of the temperature control mechanism is as follows:

When the valve is open, the chilled brine in compartment A passes through the opening 20 into the compartment B and as the brine in compartment B warms up by absorbing heat units from the storage receptacles contained within the compartment B, the warmer brine will rise to the top and flow through the tubular sleeve 21 and back into the upper part of the compartment A, where it is then rechilled and recirculated. To vary the temperature within compartment B the valve will be actuated to partially close the passageway 21, thereby partially shutting off the flow of warm brine through this passageway. As a result fewer heat units will be permitted to flow through the passageway, as the flow of the brine will be restricted. The valve thus controls the circulation of the brine so as to regulate the temperature within compartment B, depending upon the class of goods which are to be stored within the food storage receptacles contained within the compartment.

The food storage receptacles or sleeves 18 within the compartment A are preferably arranged to hold brick ice cream, while the food storage receptacles in compartment B are preferably arranged to contain bulk ice cream, which is kept at a higher temperature than the brick ice cream. Control of the refrigerating apparatus may be adjusted so as to maintain a very low temperature within the compartment A, as the brine within this compartment is in direct contact with the cooling element or evaporator. By the mechanism which controls the circulation of the brine, the temperature of the brine within compartment B is maintained higher than in compartment A, the temperature within compartment B being thus regulated by the manually operated control mechanism.

Obviously, the number of food storage re-

ceptacles is immaterial and, if desired, additional compartments may be hooked up, the circulation of the brine through the cabinet regulating the temperature within the various compartments.

Various changes can be made in the mechanism for controlling the circulation of the brine in the tank without departing from the spirit of my invention and the scope of what I claim.

What I claim is:

1. In a mechanically refrigerated cabinet, a single closed tank containing a heat absorbing fluid and provided with a partition wall dividing the tank into a plurality of adjoining compartments, said partition wall being provided with openings directly therein and adjacent its lower edge and its upper edge, thereby permitting the heat absorbing fluid to circulate from one compartment to the other, a heat transfer element extending into one of said compartments and the fluid therein, and means for varying the size of the upper opening in said partition to control the quantity of flow of the heat absorbing fluid therethrough to regulate the temperature within the compartment containing the food storage receptacles, said means being disposed closely adjacent the opening.

2. In a mechanically refrigerated cabinet, a unitary closed tank containing a heat absorbing fluid and provided with a partition wall dividing the tank into a plurality of adjoining compartments, said partition wall being provided with openings directly therein and adjacent its lower edge and another opening adjacent its upper edge, thereby permitting the heat absorbing fluid to circulate from one compartment to the other, a heat transfer element extending into one of said compartments and the fluid therein, and a butterfly valve adjacent the upper opening and manually operable from an exterior point of the cabinet for controlling the quantity of flow of the heat absorbing fluid through the openings in said partition wall to regulate the temperature within the compartment containing the food storage receptacles.

3. In a mechanically refrigerated cabinet, a unitary closed metallic tank adapted to contain a heat absorbing fluid, metallic partitions directly within and dividing said tank into a plurality of adjoining compartments, said partitions having apertures directly therein and adjacent the upper and lower edges thereof, a valve connected with one of said partitions to control the circulation of fluid through the opening adjacent the upper edge thereof, means for operating said valve extending externally of said tank, and a mechanically refrigerated heat transfer element in one of the compartments.

4. In a mechanically refrigerated food storage cabinet, a single closed tank adapted to contain a heat absorbing fluid, partitions

formed by spaced metallic plates dividing said tank into a plurality of adjoining compartments, said partitions having apertures extending therethrough adjacent the upper and lower edges thereof, said apertures permitting the circulation of the heat absorbing fluid between adjacent compartments, a butterfly valve carried by one of said partitions

for controlling the passage of fluid through the upper opening therein, means for operating the valve, and a mechanically refrigerated heat transfer element extending into one of said compartments. 10

In testimony whereof, I hereunto affix my signature.

JOHN R. REPLOGLE.
